TIME DIVISION CARRIER MULTIPLEX
TELEPHONE SYSTEM

John H. Homrighous, Oak Park, Ill.

Application July 17, 1944, Serial No. 545,206

14 Claims. (Cl. 179—15)

1

This invention relates to an improved multiplex communication system and more particularly to a system for increasing the number of messages that may be transmitted over a wired carrier channel.

One of the objects of my invention is to provide means for modulating two messages on a wired carrier for simultaneous reception.

Another object of this invention is to provide means for communicating between distant points by telephone and coded messages simultaneously over a single carrier channel.

Another object of my invention is to provide in a wired communication system carrier channels for transmitting messages of relative wide frequency bands, such as amplitude and frequency modulated radio programs, and for utilizing these same channels for transmitting two messages simultaneously of relative narrow frequency band.

Another object of my invention is to provide means for decreasing the number of transmission channels required between two points whereby the terminal apparatus and the intermediate repeater apparatus may be reduced.

Another object of my invention is to provide synchronizing or control signals from a master generator over wired carrier channels or trunk lines to the various offices throughout the system, whereby the multiplex mechanisms in these offices are maintained in synchronism.

Several messages may be transmitted simultaneously over a wired trunk line by providing a different carrier wave for each message, several audible frequencies may also be transmitted simultaneously on a single carrier, and two different messages may be transmitted over a low potential or direct current trunk line by reducing the period of time for equal portions of different messages and transmitting these portions in rotation. In the instant invention I separate the signals for two messages into small portions or fragments and reduce the period of time for each portion approximately one half and then modulate the signals on a single carrier in rotation for simultaneous reception, the multiplex mechanism in each office being controlled by synchronizing signals developed by a master generator and transmitted to all the offices in the system.

Other objects will be apparent from the following description taken in connection with the accompanying drawings in which:

Figure 1 is a block diagram showing trunking arrangements between centers or cities for wired carrier channels.

Figure 2 shows a trunk line provided with ter-

2

minal equipment for one or two party one way carrier channel, and also terminal equipment for a one or two party two way carrier channel.

Figures 3 and 4 show operator's cord circuits.

In Figure 1 the central offices 1 and 2, connected by the trunk line 3, may be located in different cities, and similar trunking arrangements may be utilized to extend wire channels to other cities. The trunk line 3 may be arranged for several carrier channels having wide frequency separation, such as a two-way two channel carrier having at one terminal a pair of jacks 4 and 5, and associated line and cut off relays 6 and 7, modulating and demodulating equipment 8 for transmitting and receiving sound or control signals, the other terminal of the trunk line being equipped in a similar manner with a pair of jacks 9 and 10 and associated line and cut off relays 11 and 12, modulating and demodulating apparatus 13 for transmitting and receiving sound or control signals for two simultaneous messages. Cord circuits 14 and 15 comprising mechanism for grouping signals in spaced periods of time and for expanding received signals, may be used to connect subscriber's lines 16 and 17 to jacks 4 and 9 of the trunk line 3. Other cord circuits similar to 14 and 15 may be used to connect two other telephone subscribers' lines not shown, or two printing telegraph lines 18 and 19 or relay control lines 20 and 21 may be connected to jacks 5 and 10 to transmit two simultaneous messages. The generators 22 are arranged to develop two different low tone frequencies for controlling the relays in line 21 individually or both together.

A one way channel may also be provided over the trunk line 3 primarily for transmitting signals for radio programs of either amplitude or frequency modulation, which may require a band width for frequencies up to eight thousand cycles for amplitude modulation and up to sixteen thousand cycles for frequency modulation. Therefore, this channel may be utilized for two telephone messages having frequencies around three thousand cycles each or for signals from two telegraph printers.

The equipment at one terminal of the one way channel may comprise a pair of jacks 23 and 24, relay apparatus 25 and 26, and modulating equipment 27; equipment may be provided for the opposite terminal in office 2 comprising a pair of jacks 28 and 29, line and cut off relay apparatus 30 and 31 and selecting and demodulating equipment 32. When using this channel for radio programs the switches 33 and 34 may be operated to the off position disconnecting the jacks 24 and

29 and associated relays from the trunk line 3. Cord circuit 35 and 36, similar to cord circuits well known in the art, may be employed to connect the radio transmitting station over lines 37 and 38 to the trunk line 3. Cord circuits 14 and 15 may be employed when it is desired to connect more than one line such as 16, 18 and 20 to the trunk line to transmit two messages at the same time.

For controlling the grouping and expanding mechanism in the several telephone offices in synchronism a master generator 39 may be employed to produce an alternating current of sine wave form preferably of ten to twenty cycles which may be transmitted over separate carriers to the distant offices in the system. Alternating current produced at 39 may be modulated on a carrier through the action of the modulation amplifier 40 and the oscillator 41. These signals may be demodulated at 42 and applied to the square wave amplifier 43 where they are amplified and clipped in a well known manner to produce equally spaced square top positive pulses to control the grouping and expanding mechanism in the cord circuits to be more fully explained later. The signals from the generator 39 are also applied to the square wave generator 44 and the output from this amplifier of spaced positive pulses may be utilized for controlling the grouping and expanding mechanism in the cord circuits for office 1.

It is to be understood that the trunk line 3 may be employed to transmit signals modulated on a carrier by transmitting the carrier or suppressing the carrier, also single side band transmission may be employed. This system may be employed on power lines, telephone trunk lines, and coaxial cable.

It is to be further understood that many other channels of carrier current may be operated over the trunk line 3.

Figure 2 shows in more detail the associated terminal equipment for the multiple channel trunk line 3. The line and cut off relays 6, 7, 11 and 12 are associated with two channels, one channel comprising the modulation amplifier 45 and the demodulator 46 for transmitting one or two messages west to east and another channel having a carrier current of a different frequency and comprising the modulation amplifier 47 and the demodulator 48 are for transmitting one or two messages east to west.

The line and cut off relays 25, 26, 30 and 31 are associated with one one way channel comprising the modulation amplifier 63 and demodulator 67 for transmitting radio program signals in one direction. Other channels may be employed on the same trunk line to transmit other telephone or telegraph messages.

The cord circuit in Figure 3 employs wire recording mechanism and associated circuits for grouping signals received over a subscriber's line in spaced periods of time and for expanding the signals received over a connected trunk line. Two of these cord circuits may connect two subscribers' lines to a single trunk line or path for the transmission over a carrier channel equal portions of two messages in successive rotation or each message may be transmitted intermittently. These cord circuits may be similar to the cord circuit shown and described in my prior application Serial Number 552,475, filed February 15, 1944, now Patent No. 2,439,701, granted April 13, 1948.

The cord circuit in Figure 4 may be similar to any conventional type cord circuit and may be employed to connect a single subscriber's line with the trunk or a single transmission path.

Referring to Figure 2, sound or control signals passing over conductors 51 from west to east are applied to the hybrid coil 52 of conventional type for converting from a four wire to a two wire circuit where they are transferred to the modulation amplifier 45 and modulated on a high frequency carrier produced by the oscillator 53. The filter 54 may be employed to remove the undesired products of modulation to preferably transmit only a single side band over the trunk line 3. At the opposite or east terminal the signals are applied to the selector 56 for filtering out all undesired frequencies; from the selector 56 the signals are detected or demodulated at 46 and applied to the hybrid coil 57 to be transferred to conductors 58. Sound or control signals directed from east to west may be applied from conductors 58 to the hybrid coil 57 where they are transferred to the modulation amplifier 47 and modulated on another high frequency produced by the oscillator 59, from the amplifier 47 the signals may pass through the filter 60 to eliminate all frequencies except a single side band for transmitting over the trunk line 3 through a different channel or path. At the west terminal the signals may be applied to the selector 61 where all frequencies are blocked except the desired signals. At 48 the signals are detected and applied to the hybrid coil 52 where they may be transferred to the conductors 51.

From the above description it has been shown that message signals may be directed from west to east over one channel and a different channel or path is employed for the return signals from east to west.

For the transmission of radio programs I have shown a one way channel. Sound or control signals from the conductors 62 may be applied to the modulation amplifier 63 and modulated on a high frequency carrier produced by the oscillator 64. The filter 65 may suppress the carrier for single side band transmission. From the filter the signals will pass over the trunk line 3 to the distant office where they will be selected by 66 and applied to the demodulation amplifier 67. After detection the signals are supplied to the conductors 68.

It is to be understood that a carrier and one side band may also be employed rather than single side band transmission.

With further reference to Figure 2, the conductors 51 and 58 terminate in a pair of jacks in parallel for connecting two cord circuits to the same carrier channels for the transmission and reception of two different messages simultaneously. Jacks 4 and 9 may be known as the A party jacks and the jacks 5 and 10 may be known as the B party jacks. Associated with each jack are line and cut off relays. The line relay or drop signal 69 associated with the A party jack at the west terminal is adapted to be actuated by alternating current supplied from a cord circuit connected to the A party jack 9 at the east terminal, and the cut off relay 70 associated with jack 4 is energized over the sleeve conductor of jack 4 from battery in the connecting cord circuit. Adapted to be operated in like manner are the line relays 71, 72 and 73 and the cut off relays 74, 75 and 76 associated with the 75 jacks 5, 9 and 10 respectively. The cut off relays

74 and 76 associated with the B party jacks are adapted to be energized through resistors 77 and 78 to affect certain changes in the connecting cord circuit to be explained later. The energization of any line relay 69, 71, 72 or 73 will cause its associated signal lamp 79, 80, 81 or 82 to glow notifying the operator that a connection is desired. Spaced pulses from the square wave amplifier 44 are applied to the signal control relay 83 to alternately energize and deenergize the relay during equal periods of time. The relay 83 in its deenergized position maintains a closed circuit through the line relay 69 at contacts 84 and holds the circuit through the line relay 71 open at contacts 85. The relay 83 upon energizing holds the circuit of relay 69 open at contacts 84 and closes the circuit for relay 71 at contacts 85 so that the line relays 69 and 71 are alternately placed in condition to be actuated by ringing current over the carrier channel for equal periods of time. Therefore, the relays 69 and 71 may be actuated by ringing current from the cord circuits connected to jacks 9 and 10 to be more fully explained later.

The relay 86 at the east terminal will be energized and deenergized from spaced pulses supplied from the square wave amplifier 43 to open and close the circuits through the line relays 72 and 73 at contacts 87 and 88 during equal periods of time. Therefore, the relays 72 and 73 may be actuated by signal current supplied through jacks 4 and 5. The relays 83 and 86 will be energized and deenergized in synchronism since all control pulses are supplied by one master generator 39 as explained in connection with Figure 1. Similar terminal apparatus and circuits may be employed for other carrier channels.

From the above description it has been shown that an operator may be signalled in either direction for the A or B party over the carrier current channels.

Should it be desired to employ the carrier channels for only one message rather than two simultaneous messages, then dummy plugs may be inserted in the B party jacks 5 and 10 and the switches 89 and 90 operated to open the circuit for relays 71 and 73, and to maintain the line relays 69 and 72 across the conductors 51 and 58 without being interrupted by the action of relays 83 and 86.

The conductors 62 and 68 for the one way radio program channel terminates in a pair of jacks in parallel for connecting two cord circuits to the same channel for the transmission of two different messages simultaneously when not in use for radio programs. Jacks 23 and 28 may be known as the A party jacks and jacks 24 and 29 may be known as the B party jacks. Associated with jacks 23 and 24 are relays 25 and 26 connected to the sleeve conductor of the jacks to produce certain effects in the connecting cord circuits to be explained later. Relay 26 is adapted to be energized through a resistor 91. Associated with jacks 28 and 29 are line and cut off relays. The line relays or drop signals 92 and 93 associated with the jacks 28 and 29 are adapted to be operated by alternating current supplied from cord circuits connected to the jacks 23 and 24 respectively, and the cut off relays 94 and 95 associated with jacks 28 and 29 are energized over the sleeve conductors of these jacks from battery in the connecting cord circuits. The cut off relay 95 is adapted to be energized through resistor 96 to affect certain changes in the cord circuit. The energization of line relays 92 or 93

will cause its associated signal lamp 97 or 98 to glow notifying the operator that a connection is desired. Spaced pulses from the square wave amplifier 43 are applied to the signal control relay 99 to alternately energize and deenergize this relay during equal periods of time. The relay 99 in its deenergized position maintains a closed circuit through the line relay 92 at contacts 100 and holds the circuit through relay 93 open at contacts 101, so that the line relays 92 and 93 are alternately placed in condition to be actuated by ringing current over the carrier channel during equal periods of time. Therefore, the relays 92 and 93 may be separately actuated by ringing current from the cord circuits connected to jacks 23 and 24.

The relay 99 will be energized and deenergized from spaced pulses supplied from the square wave amplifier 43 to open and close the circuits through the line relays 92 and 93 at contacts 100 and 101 during equal periods of time.

From the above description it has been shown that an operator may be signalled from either the A or B party jack over a one way carrier current channel.

When it is desired to employ the one way channel for radio program transmission the keys 33 and 34 would be operated disconnecting the B party jacks and associated equipment from the channel conductors 62 and 68 and maintaining the circuit of relay 92 across conductors 68 without being interrupted through the action of relay 99.

With reference to Figure 3, which shows a cord circuit for connecting a telephone line, or a printing telegraph line, or a relay signalling line to a multi-party carrier channel of Figure 2 as illustrated in Figure 1 at 14 and 15. The cord circuit includes recording and reproducing mechanism for grouping and separating sound signals so that two cord circuits may be employed at each terminal of the trunk or carrier channel for transmitting two separate and private messages over a carrier trunk at the same time.

The plug 102 is a calling or answering plug for the subscriber's lines, and the plug 103 is a calling or answering plug for the trunk line or carrier channel. Battery at 104 is fed to the telephone or other subscriber lines through the resistance 105, secondary winding of transformer 106, winding 107 of anti-sidetone transformer 108. The operator may ring on the telephone line through the action of key 109, and she may talk to the telephone subscriber by operating the key 110. The usual disconnect signal is provided at 111, which is caused to glow by the relay 112 returning to normal position when the subscriber on the connected line hangs up his receiver. Key 109 would not be operated when the cord is connected to a printing telegraph or relay signalling line. Battery at 113 is fed through resistor 114, conductors 115 and 116 when certain relays in the cord circuit are operated, to be explained later, secondary winding of transformer 117, winding 118 of the anti-tone transformer 119, tip of plug 103, conductors 51 or 58 in Figure 2, through a four wire two wire hybrid coil 52 or 57, ring of jack 103 to opposite side of battery. A disconnect signal is provided at 120 which may be actuated by the relay 121.

Assume that the plug 103 is connected to the A jack 4 in Figure 2; then relays 70, 122 and 123 would be energized in series over the sleeve conductor. Relay 70 upon energizing clears relay 75 69 from the conductors 51. Relays 122 and 123

upon energizing completes a circuit from the square wave amplifier 44, conductor 124, springs 125, springs 126 and 127 to relay 128. Therefore relay 128 is energized and deenergized during equal periods of time by the spaced pulses from the amplifier 44. Relay 128 in its normal or deenergized position shorts the very high resistance 129 over conductor 115, springs 130, springs 131, conductor 116. The duration of this condition may be considered one talking period for the A party. Ringing current may be sent out over the channel by operating the key 132 during the A party interval through springs 133 and 134 to operate the relay 72. Should the plug 103 be connected to the B jack 5 ringing current may be supplied to the conductors 51 during the B party interval through the contacts 135 to operate relay 73. Relay 128 during the period that it is energized opens the contact springs 130 to include the resistance 129 in the battery circuit feeding the tip and ring conductors, thereby rendering the cord circuit inoperative or blocked to sound signals, which may be known as the B party talking period. Since the control signals are in synchronism relays 83, 86 and 128 will be operated in unison, and line relay 72 will be cleared from the line during the B party talking period.

In order that two messages may be transmitted over a single channel, I reduce the interval of portions or fragments of each message by approximately one half and transmit these grouped portions in alternate periods of time. Therefore, by recording the signals from the subscriber's line or the operator's telephone set on a magnetic wire or tape and reproducing the signals by a coil traveling in the opposite direction to that of the wire and at approximately the same speed, the interval for each portion will be reduced and the frequency of the signals will be increased.

The sound signals from a connected telephone line or the variable signals from a printing telegraph or low tone subscriber's line would pass through the cord tip conductor, winding 107, and the alternating current component seeking the path of least impedance would pass through windings 136 and 137 of the transformer 108, condenser 138 to ring conductor. The primary winding of audio transformer 139 bridged across the winding 136 of transformer 108 will vary the potential on the grid 140 of the amplifier tube 141 in accordance with signals received over the subscriber's line. The anode output of tube 141 may be applied through the transformer 142 to the stationary recording coil 143 for recording the signals magnetically on the moving wire or tape 144.

In the recording and reproducing mechanism I preferably employ an endless wire 144 of small diameter traveling in the direction indicated by the arrows over the pulleys 145, 146, 147, 148, 149 and 150. The pulley 148 is driven at a uniform speed by a motor 152 through the friction clutch indicated by the dashed circle 153. Attached to the pulley 148 is a disk of larger diameter 154, driving the member 155 on the slide bars 156 and 157 in a reciprocating motion through the action of the connected arm 158 attached near the rim of the disk 154 so that the distance traveled right to left by the member 155 is approximately equal to the distance traveled by the wire in one half revolution of the pulley and disks 148 and 154.

The signals recorded on the wire 144 by the coil 143 may be picked up by the reproducing coil 159 traveling from right to left or in a direction reverse to that of the wire so that the sig-

nals will be reproduced in the coil 159 in one half of the interval that was required to record them on the wire. The coil 159 traveling from left to right moves very nearly at the same speed and in the same direction as the wire. Therefore the coil 159 would be inactive and as will be shown later the signals would be blocked in the cord circuit during the left to right movement of the coil.

The signals reproduced by the coil 159 are applied to the grid 160 of the amplifier tube 161. The output of tube 161 is applied to the primary winding of transformer 117 to vary the current supplied by battery 113 to the trunk line over a path as previously described. Therefore, it has been shown that the sound signals from the subscriber's line may be separated into small portions, and grouped by the interval being reduced through the reciprocating action of the coil 159, and then transmitted over the carrier channel in spaced periods of time. As shown in Figure 1 another cord circuit 15 may be employed in office 2 to connect a telephone line or printing telegraph line with the A jack 9 of the trunk line. This cord circuit as previously stated may be exactly like the cord circuit of Figure 3. Therefore, signals originating in office 2 and transmitted over the trunk line would also be in spaced groups and the alternating current component would flow through windings 118, 162 and 163 of the anti-sidetone transformer 119, condenser 164 to the opposite side of the line. The primary winding of transformer 165 bridged across the winding 162 will cause the potential on the grid 166 of amplifier 167 to vary in accordance with the sound signals received from the carrier channel. The anode output of tube 167 is applied through the audio transformer 168 to the recording coil 169 mounted on the member 155 and traveling forward and backward along the wire 144 to record sound signals thereon during the right to left movement of the coil only. The coil travels left to right in the same direction and approximately the same speed as the wire, therefore no signals would be developed. Furthermore the cord circuit will be blocked during this period by including the resistor 129 in the battery supply circuit. The coil 159 in moving right to left along the wire 144 in a direction opposite to the movement of the wire will cause the signals to be recorded over a length of the wire 144 equal to approximately twice the distance that the coil 169 travels right to left, so that the signals received over the trunk line will be expanded to their normal interval and reproduced in the stationary coil 170 and applied to the grid 171 of the amplifier tube 172. The anode output of tube 172 may be applied to the primary winding of the transformer 106 to vary the current in the telephone line over a path as previously described.

The coils 173 and 174 are high frequency erasing coils for restoring or demagnetizing the wire 144 so that further messages may be recorded thereon.

The pole pieces for the recording and reproducing coils are provided with a narrow slot for the wire 144 to travel through.

The A party talking periods over the carrier channel or trunk line are the periods between synchronizing pulses, and the B party talking periods are during the intervals of the synchronizing pulses, which are the same in each two party channel or path throughout the system. In other words, signals originating in office 1 and

transmitted over A party trunk would be transmitted during the intervals between control pulses and the answer from a subscriber in office 2 would also be transmitted during the intervals between control pulses.

In order to synchronize the grouping and separating mechanism with the proper party A or B on the trunk line, I provide holding or retarding magnets 175 and 176 for holding the disk 154 so that the member 155 will be held or retarded until a control pulse is received. The magnet 175 may be considered the A party holding magnet and in its nonoperated position as shown in the drawing it holds the disk 154 from rotating by the armature bar 177 engaging the pin 178 in the disk 154. As soon as a control pulse is received over conductor 127, the magnet 175 is energized in parallel with relay 128 through springs 125, 126 and 127, and conductor 179, during the intervals of the control pulses to permit the disk 154 to rotate. The motor is arranged to drive the disk a little faster than one revolution per cycle of the control signals so that the bar 177 will slightly retard the disk just before the control pulse is received. The magnet 176 is continuously energized while the plug 106 is connected to the A party jack through the springs 180, 181 and 182 and the conductor 183, to hold its armature bar 184 out of engagement with pin 185.

From the above it has been shown that the member 155 will move from right to left while the relay 123 is deenergized to transmit sound signals during the intervals between control pulses, and that during the intervals of the control signals the cord circuit is blocked by including the resistance 129 in the talking path. As previously explained another cord circuit similar to Figure 3 will be employed in office 2 so that a subscriber in office 1 and a subscriber in office 2 may talk over the A party channel or trunk line. A second subscriber in office 1 may talk to a second subscriber in office 2 at the same time over the B party channel or path. In which case another cord circuit similar to Figure 3 would be connected to the B jack 5 in office 1, and a similar cord circuit would be connected to the B jack 10 in office 2.

Inserting the plug 103 into the B jack 5 will cause relays 74 and 123 to be energized through the resistance 77 over the sleeve conductors, relay 122 is arranged so that its armature will not be operated when the resistor 77 is included in its energizing circuit. Therefore relay 186 will be energized intermittently by the control signals over conductor 124, and through the springs 125, 126 and 187 to the relay 186. Relay 186 during its energized position may be considered the B party talking period and the resistor 129 is shortened at spring 188 during the intervals of the control pulses, and in the intervals between pulses the resistor 129 is included in the talking path to block the signals and to reduce the current drain. Instead of using the resistor 129 the talking path could be opened and closed by the relay 186. The holding magnet 176 will be operated in unison with the relay 186 over conductor 123 and springs 126 and 125, to retard the rotation of the disk 154 by the armature arm 186 engaging the pin 185, which places the member 155 in position to start moving to the left at the instant a control signal is received. Holding magnet 175 is held in its operated position when the cord is used with B party trunk lines, over conductor 179 through springs 189, 181 and 180 to ground. The remainder of the apparatus and associated cir-

cuits in the cord functions as described in connection with the A party.

From the above it has been shown that two private messages may be transmitted over a single channel by grouping the signals in alternate spaced periods, and also that the operator may be signalled in either direction. It is also shown that the cord circuit of Figure 3 may be used for either A or B connections.

10 The cord circuit of Figure 3 may be used with the one way channel circuit in the same manner as described above for the two channel two way circuit except that signals would only be transmitted from west to east. Also the operator would only be signalled in one direction. The operation of ringing key 132 would cause ringing current to be sent out over the carrier channel during a period depending upon which party jack is used. Should plug 103 be inserted in the A party jack then ringing current will only be supplied to the carrier channel during the A party intervals through springs 133 and 134, and when the plug 103 is connected to a B jack ringing current will only be supplied to the channel during the B party interval through the contacts 135.

25 The message signals in the trunk line are in spaced intervals, but after passing through the cord circuit they are again connected together in a continuous message. Hence the telegraph and relay tone signals in the called line will be like the original signals in the calling line.

30 When it is desired to use the one way channel circuits or the two way double channel circuits for only one message at a time rather than two simultaneous messages the keys 33 and 34 would be operated to disassociate the B party apparatus from the trunk line, and the switches 89 and 90 would be operated to disconnect the B party line relay from the trunk line, and the cord circuit of Figure 4 would be used as illustrated at 35 and 36, Figure 1.

35 Figure 4 shows a conventional cord circuit provided with a pair of plugs 193 and 194, ringing keys 195 and 196, listening key 197 and a signal lamp to indicate subscriber's disconnect. This cord circuit to be used when it is desired to connect a radio transmitting station or any time it is desired to transmit a message having a very wide frequency band.

40 In the various circuits shown and described I have simplified the drawings by indicating the source of potential by a positive or negative sign. Also I have omitted the heater elements from the various tubes.

45 The embodiments of the invention which have been given herein are illustrations of how the various features may be accomplished and of the principles involved. It is to be understood that the invention contained herein is capable of embodiments in other forms and adaptations, without departing from the spirit of the invention and the scope of the appended claims.

50 I claim:

1. In a telephone system, a trunk line provided at one terminal with a pair of jacks and a relay for each jack, an oscillator for producing a carrier current channel for said trunk line, means for actuating either one of said relays independently over said channel, and switching means for disconnecting one of said jacks and its associated relay from said trunk line.

65 2. In a telephone system, first and second telephone offices, a trunk line extending between said offices adapted for simultaneous transmission of a number of carrier waves, a pair of jacks as-

11

sociated with each terminal of said line for each of the said carrier waves, a signal associated with each of the said jacks for informing an operator that a connection is desired, a link circuit adapted to be connected to the said jacks in said first office, and means in said link circuit connected to a jack in the first office to intermittently supply signalling current to said line to modulate one of said carrier waves, thereby actuating a signal in said second office to indicate the jack for answering the call.

3. In a communication system, a trunk line adapted for the simultaneous transmission of a number of carrier waves, a pair of jacks associated with said line for each of the said carrier waves, a plurality of link circuits each provided with plug-in terminals for connecting with anyone of said jacks, said link circuits comprising mechanism for grouping electrical signals, and means including two of said link circuits for transmitting signals representative of two simultaneous messages over any one of said carrier waves.

4. In a telephone system, first and second telephone offices, a trunk line extending between said offices adapted for simultaneous transmission of a number of carrier waves, a pair of jacks associated with each terminal of said line for each of the said carrier waves, a signal associated with each of said jacks for informing an operator that a connection is desired, link circuits in each of said offices adapted to be connected to said jacks, each of said link circuits comprising mechanism for grouping electrical signals, means in said link circuit connected to a jack in the first office for actuating a signal in said second office to indicate the jack for connecting another link circuit to answer the call, means following the connection of the second link circuit for transmitting signals representative of a telephone message from the first office to the second office over one of said carrier waves in spaced periods of time, a generator at said first office for producing control signals, means for transmitting said control signals to said second office, and means at said offices responsive to said signals for controlling the grouping mechanism in both offices in synchronism.

5. In a telephone system, first and second telephone offices, a trunk line extending from the first office to the second office, means at the first office to produce a carrier wave, means to transmit said carrier wave over said trunk line, a first pair of subscriber's lines at said first office, a first pair of cord circuits for interconnecting said subscriber's lines to said trunk line, means in said cord circuits to select different portions of the signals representative of two telephone messages received from said pair of lines, means to modulate the selected signals for both messages in rotation on said carrier wave, a second pair of lines at said second office, a second pair of cord circuits for interconnecting said second pair of lines to said trunk line, and means in said second pair of cord circuits to select the signals received over said carrier wave to transmit separate telephone messages over each line of said second pair of lines.

6. In a communication system, a trunk line, means to receive from said trunk line different sets of control signals, means to receive from said trunk line control impulses, a first line and a second line each provided with a relay, a pair of cord circuits for connecting said first and said second lines to said trunk line, means in one of

12

said cord circuits under control of said impulses to select a first set of said control signals to transmit the selected signals over said first line to control its associated relay, and means in another one of said cord circuits under control of said impulses to select a second set of said control signals to transmit the second set of signals over said second line to control its associated relay.

10 7. In a telephone system, a trunk line, means to produce a number of carrier waves, means to transmit said carrier waves over said trunk line, a pair of jacks associated with said trunk line for each of the said carrier waves, a plurality of link circuits each provided with plug-in terminals for connecting with any one of said jacks, each of the said link circuits comprising means to select different portions of electrical signals, representative of a telephone message, and means including two of said link circuits to modulate signals for two telephone messages on any one of said carrier waves in recurring intervals.

15 8. In a telephone system, a subscriber's line, a trunk line provided with means for generating a carrier wave, a cord circuit for connecting said subscriber's line to said trunk line, a generator to produce control waves, an amplifier, means including said amplifier to produce spaced control impulses from said control waves, and means in said cord circuit under control of said impulses for separating sound signals received from said subscriber's line into equal portions, and for reducing the interval of each portion to modulate said carrier wave during spaced periods of time, 20 said last means comprising devices for recording said signals on a movable telephone wire and movable devices adapted to travel in a direction opposite to said wire for reproducing said signals in space periods.

30 9. In a communication system, a line, a trunk line provided with means for developing a carrier wave, a cord circuit for connecting said first line to said trunk line, means to produce control waves, an amplifier, means including said amplifier to produce spaced control impulses from said control waves, and means in said cord circuit under control of said impulses to group signals received from said first line into spaced portions to modulate said carrier wave during spaced 35 periods of time, said last means comprising devices for recording said signals on a movable telephone wire and movable devices adapted to travel in a direction opposite to said wire for reproducing said signals in groups.

40 10. In a communication system for the transmission of at least two sets of control signals, a trunk line terminating into a first branch line and a second branch line, means for producing a carrier wave, means including said carrier wave for transmitting said control signals in like manner over said trunk line, a generator to produce control waves, an amplifier, means including said amplifier to produce spaced synchronizing impulses from said control waves, means to produce a second carrier wave, means including said second carrier wave to transmit said control waves over said trunk line, means comprising apparatus and suitable circuits under control of said synchronizing impulses to select one of said sets of control signals to transmit the selected control signals over said first branch line, and means comprising other apparatus and associated circuits under control of said synchronizing impulses to select a second one of said sets of con-

trol signals to transmit the second set of control signals over said second branch line.

11. In a telephone system, a first and a second telephone office, a trunk line extending from said first office to said second office for transmitting signals modulated on a carrier wave, signal selecting means in said first office including a first movable member to select portions of said signals corresponding to two telephone messages to modulate said carrier wave with the selected portions of said signals for each message in a different recurrent period of time, means in the second office including a second movable member for separating the selected portions of said signals received over said trunk line, a generator at said first office to produce control signals, means to transmit the said control signals to said second office, means at said first office including a first electric device responsive to said control signals for controlling said selecting means, and signal separating means at said second office including a second electric device responsive to said received control signals for controlling said separating means.

12. In a telephone system, a trunk line provided at one terminal with a pair of jacks, and a relay for each jack at the opposite terminal, an oscillator to produce a carrier wave, means to transmit said carrier wave over said trunk line, a cord circuit having a plug for detachably connecting the said cord circuit through either one of said jacks to said trunk line, and means in said cord circuit to intermittently supply signaling current to said trunk line to modulate said carrier wave during different recurring periods depending upon the jack connected with the cord circuit to actuate the said relay associated with the connected jack.

13. In a telephone system, a trunk line, means to produce a carrier wave, means to transmit said carrier wave over said trunk line, a pair of subscriber's lines, a pair of cord circuits for interconnecting said subscriber's lines to said trunk line, and means including a movable member in each of the said cord circuits to modulate said carrier wave with portions of the message signals

transmitted simultaneously over said pair of lines in a different recurrent period for each message.

14. In a telephone system, a trunk line extending from a first office to a second office, means in the first office to produce a carrier wave, means to transmit said carrier wave over said trunk line, means in the first office to produce control waves, amplifier means responsive to said control waves to produce spaced control signals, means to transmit said control waves to the second office, a plurality of relays in the second office associated with said trunk line, amplifier means in the second office responsive to received control waves to produce spaced synchronizing signals, electro-magnetic means in the second office under control of said synchronizing signals to connect the said relays in successive rotation to said trunk line, and electro-magnetic means in the first office under control of said control signals to cause ringing current to be modulated on said carrier wave during a certain recurrent period to energize one of said relays.

JOHN H. HOMRIGHOUS.
